MERCHANTISE HOLDER

Reginald B. Meller, Oakland, Calif.

Application April 30, 1941, Serial No. 391,052

10 Claims. (Cl. 211—71)

My invention relates to a merchandising device, and more particularly to a holder for individual items of merchandise, such as bottles, cans, or the like.

Among the objects of my invention are—

(1) To provide a novel and improved merchandise holder which lends itself to rapid loading or packing;

(2) To provide a novel and improved merchandise holder which offers maximum display possibilities to the merchandise;

(3) To provide a novel and improved merchandise holder which automatically locks and holds the individual items of merchandise against accidental displacement or removal;

(4) To provide a novel and improved merchandise holder wherein the items held therein contribute toward the efficient functioning of the device;

(5) To provide a novel and improved merchandise holder which is exceedingly simple in construction and which lends itself to high speed production methods both in the matter of manufacture and use;

(6) To provide a novel and improved merchandise holder which will efficiently simplify the packing of such merchandise for shipment.

Additional objects of my invention will be brought out in the following description of the same taken in conjunction with the accompanying drawing wherein—

Figure 1 is a view in perspective of a preferred form of my invention;

Figure 2 is a view in cross section, taken on the line 2—2 of Figure 1;

Figure 3 is a view corresponding to that of Figure 2, but showing the stressed condition of the device while loading merchandise therein;

Figure 4 is a view similar to Figure 3, showing the condition of the device with the merchandise in its final position;

Figure 5 is a view illustrating a blank from which my novel and improved merchandise holder may be assembled.

In general, my invention is in the form of a trough-shaped device adapted to function as a holder to receive and hold merchandise such as bottles, cans, or the like which are formed with a ridge at the bottom thereof, whereby the items may be locked in position against accidental displacement or removal.

Referring to the drawing for a more detailed description of the device in its preferred form, it comprises a trough 7, preferably of flexible material, and includes a pair of side walls 9 re-

silently hinged to an intermediate floor section 11.

The side walls are provided with notches 13 therein at spaced intervals adjacent the floor section 11, with the notches of one wall disposed directly opposite to the notches of the other wall;

The floor section is formed with integral laterally extending tabs 15 at those locations where the side walls are notched, such tabs extending beyond the side walls.

Each of the side walls is supported and braced by a bracing wall 17 joined to its associated side wall along the upper edge thereof, and anchored to the undersurface of the floor section 11, after being folded over and turned under the free edges of the laterally extending tabs 15. The side walls 9 are preferably first adjusted, however, to toe inwardly at an acute angle to the floor section 11, and while in this position, the bracing walls are formed as previously indicated, the tabs offering a suitable means for facilitating the creasing of the bracing walls along the proper crease line in forming the turned-under portions 18. In securing the bracing walls to the floor section, the free edge only of the turned-under portion 18 of each bracing wall is affixed to the floor section and along a region adjacent the longitudinal axis thereof, thus leaving the greater part 19 of each turned-under portion unattached and movable with respect to the floor section. This leads to added advantages of considerable merit, in the functioning of my improved device, as will be pointed out in describing the operation thereof.

The merchandise holder of my invention is designed to hold items 21 such as bottles, cans, or the like which are formed with a peripheral ridge 23 at the bottom thereof, and with respect to the particular item for which the device is designed, the distance between opposite notches 13 in the device should be slightly less than the diameter of the item in the plane of the ridge 23.

Each item is assembled by forcing it, bottom downward, between the side walls 9, causing them to spread and become stressed in such a manner as to develop a reactive restoring force against the item, in the direction of the arrows in Figure 3. This force is considerably enhanced by the presence of the bracing walls 17 and the fact that the bracing walls are resiliently hinged to the floor section 11, at a distance from the side edges thereof, thus offering considerable leverage in opposing the spreading of the side walls 9. It is to be noted that during such spreading,

the bracing walls 17 tend to swing, each about its respective hinge axis, which lies along the region of attachment to the floor section 11, and such movement causes the unattached part 19 of the turned-under portion of each bracing wall to flex away from the floor section.

As the item is pushed home to its final position in contact with the floor section 11 of the device, the ridge 23 snaps into a pair of oppositely disposed notches 13, permitting the side walls 9 to initiate a return movement in the direction of their normal position, thereby locking the item in place. Complete restoration of the side walls to their normal position is precluded by the presence of the item itself which, as a result, is placed under pressure-engagement by the side walls, leaving the turned-under portions 18 of the bracing walls still partially flexed away from the floor section, as indicated in Figure 4. Such partial flexing of the turned-under portion of each bracing wall is of considerable importance in the efficient operation of my device, since it enables the items themselves to create or set up forces in the device, which will aid those restoring forces already existing in the stressed portions, and thereby increase the holding or locking effect of the device and provide a much firmer grip on the items. This may be explained by pointing out that as the loaded device is set upon a flat surface such as a counter or shelf, the weight of the items held therein will be distributed equally to the bracing walls and thereby produce a reactive force upwardly against each bracing wall. By reason of the construction of each bracing wall and its hinged connection to the floor section, such reactive forces as will be induced by the weight of the items, will be in directions to supplement the restoring forces already existing in the device, thereby increasing the pressure-engagement between the side walls and the item and effecting a much firmer grip on the item.

The side walls 9 are preferably low in height to form a shallow trough, whereby substantially the entire merchandise may be exposed for display purposes, and may be removed, item by item as desired, merely by spreading the side walls and lifting the item out.

The bracing walls, at the same time, offer substantial space for carrying advertising matter or directions as to the manner of use of the merchandise carried in the holder.

In addition to the advantages already attributed to my device, it also offers many advantages in the packing and shipping of merchandise, as the use of my holders assures proper spacing of the merchandise items and holds them against accidental displacement. Therefore, the need for packing material or partitioning compartments is eliminated, and practically no waste is incurred, as the same holders are used in the displaying and selling of the merchandise after unpacking the same from the container in which they have been shipped.

By reason of the supporting effect of the bracing walls and the forces developed in my device, as previously explained, the device can be and preferably is made from cheap flexible material such as paper or the like, having a certain degree of resiliency. A single such device may very economically be formed from a rectangular blank, and of interest in this connection is the fact that the preparation of such blank need not involve the slightest waste of material, as clearly indicated in Figure 5 which depicts a blank from

which one such device may be formed. With reference to this figure, the components of the device are indicated by primed reference numerals corresponding to the unprimed numerals employed in the previous figures. The portion forming the floor section 11' runs through the middle of the blank and is defined by two rows of cuts forming the tabs 15' which in turn are joined by score lines 25. Spaced from each row of tab cuts is a score line 27 to determine the height of each side wall 9', the remainder of the blank adjacent each side wall 9', being dedicated to the formation of a bracing wall 17'. A score line 29 through each of these remaining portions of the blank will facilitate bending or creasing the bracing wall 17' around the free ends of the tabs 15' during assembling.

The notches 13 of the assembled device come into existence upon assembling the blank, and as will be apparent from the drawing, these notches are determined by the same cuts which define the tabs. Although the cuts may be made to provide rectangular notches, notches which are rhomboidal in shape are preferable, as they afford a better hold on the item to be secured, and will inherently compensate for varying thicknesses in the ridge.

While I have disclosed a blank from which to assemble a single device, the devices may be manufactured in quantity under high speed methods, by providing the cuts and score lines in blank material as it is removed in ribbon form from a suitable roll, and in a continuous operation, assembling the material as it is so cut and scored, and then cutting off sections to desired length, which length will be determined by the number of items that each device is intended to hold.

The completed holder thus provides a cheap but efficient and attractive means for holding and displaying merchandise of the character described, and one offering many advantages. Although the device has been described as a holder for bottles or cans having a ridge at the bottom thereof, merchandise in bags may similarly be retained in the device by stitching a ridge around the bottom edge of each bag.

While I have described what I consider the preferred form of my invention, it is apparent that the same may be modified, without departing from the spirit thereof, and I accordingly do not desire to be limited in my protection, except as may be necessitated by the prior art and the appended claims.

I claim:

55 1. A merchandise holder, preferably for items such as bottles, cans or the like having a peripheral ridge at the bottom thereof, comprising, a trough of flexible material including a floor section, a pair of side walls having portions thereof terminating short of said floor section to provide space for the reception of such peripheral ridge upon the insertion of a can or the like in said trough; and a supporting wall for each of said side walls, said supporting wall being joined along 60 one of its edges to its associated side wall adjacent the upper edge thereof and along its opposite edge to said floor section, and disposed at an acute angle with respect to said floor section.

65 2. A merchandise holder, preferably for items such as bottles, cans or the like having a peripheral ridge at the bottom thereof, comprising, a trough of flexible material including a floor section having laterally extending tabs, a pair of side walls connecting with said floor section and 70 having portions thereof terminating short of said

floor section; and a supporting wall for each of said side walls, said supporting wall being joined along one of its edges to its associated side wall adjacent the upper edge thereof and folded over and under said floor section tabs and affixed to said floor section.

3. A merchandise holder, preferably for items such as bottles, cans or the like having a peripheral ridge at the bottom thereof, comprising, an open top trough of flexible material having side walls and a floor section intermediate said side walls, said side walls being resiliently hinged to said floor section to permit stressed spreading of said walls for the insertion of such item through the open top of said trough, and notched at spaced intervals adjacent said floor section, to receive said ridge and at least partially relieve the stressed condition of said side walls whereby to hold such item against displacement and a supporting member connected to each side wall at the top thereof and at an angle thereto, said member being disposed to overlie a side of said trough and to be folded thereunder and affixed thereto, to normally position said side wall at an acute angle to said floor section.

4. A merchandise holder, preferably for items such as bottles, cans or the like having a peripheral ridge at the bottom thereof, comprising, a trough of flexible material having side walls, each notched at spaced intervals adjacent the bottom edge thereof, a floor section joining said side walls along the bottom edges thereof and having spaced tabs extending beyond said side walls; a bracing wall for each of said side walls, said bracing wall being joined to the upper edge of a side wall and folded over and under those floor section tabs extending beyond said side wall; and means affixing the turned-under portion of such bracing wall to the undersurface of said floor section.

5. A merchandise holder, preferably for items such as bottles, cans or the like having a peripheral ridge at the bottom thereof, comprising, a trough of flexible material having side walls, each notched at spaced intervals adjacent the bottom edge thereof, a floor section joining said side walls along the bottom edges thereof and having spaced tabs extending beyond said side walls; a bracing wall for each of said side walls, said bracing wall being joined to the upper edge of a side wall and folded over and under those floor section tabs extending beyond said side wall, and means affixing the turned-under portion of such bracing wall to the undersurface of said floor section along a region of said floor section spaced from the side thereof.

6. A merchandise holder, preferably for items such as bottles, cans or the like having a peripheral ridge at the bottom thereof, comprising, a trough of flexible material having side walls, each notched at spaced intervals at the bottom edge thereof, a floor section joining said side walls along the bottom edges thereof between said notches; a bracing wall exceeding in width that of a side wall for each of said side walls, said bracing wall being joined adjacent the upper

edge of a side wall and folded under said floor section in spaced relationship to said side wall to normally dispose said wall at an acute angle to said floor section; and means affixing the turned-under portion of such bracing wall to the undersurface of said floor section.

7. A merchandise holder, preferably for items such as bottles, cans or the like having a peripheral ridge at the bottom thereof, comprising, a trough of flexible material having side walls, each notched at spaced intervals adjacent the bottom edge thereof and toed in toward each other, a floor section joining said side walls along the bottom edges thereof and having spaced tabs extending beyond said side walls; a bracing wall for each of said side walls, said bracing wall being joined to the upper edge of a side wall and folded over and under those floor section tabs extending beyond said side wall; and means affixing the turned-under portion of such bracing wall beneath said floor section along a region spaced from the edge of said floor section.

8. A merchandise holder, preferably for items such as bottles, cans or the like having a peripheral ridge at the bottom thereof, comprising, a trough of flexible material including a floor section, a pair of side walls having portions thereof terminating short of said floor section; and a supporting wall for each of said side walls, both said side walls and supporting walls being normally toed inwardly to make interior angles with the floor section of less than 90°.

9. A merchandise holder, preferably for items such as bottles, cans or the like having a peripheral ridge at the bottom thereof, comprising, a trough of flexible material including a floor section, a pair of side walls connecting with the floor section and having portions thereof terminating short of said floor section, and a bracing wall for each of said side walls, said bracing wall being joined along one of its edges to its associated side wall adjacent its upper edge and folded under and secured to said floor section along a region spaced from the edge of said floor section, leaving a portion of the under-turned section of said bracing wall free to flex away from the floor section.

10. A merchandise holder, preferably for items such as bottles, cans or the like having a peripheral ridge at the bottom thereof, comprising, a trough of flexible material including a floor section, a pair of side walls connecting with the floor section and having portions thereof terminating short of said floor section, and a bracing wall for each of said side walls, said bracing wall being joined along one of its edges to its associated side wall adjacent its upper edge and folded under and secured to said floor section along a region spaced from the edge of said floor section, leaving a portion of the under-turned section of said bracing wall extending beyond the edge of said floor section and free to flex away therefrom.
